UNITED STATES PATENT OFFICE.

HAROLD BRAUNTON, OF SAN FRANCISCO, CALIFORNIA.

IGNITION SYSTEM FOR ROTARY OSCILLATING-CYLINDER ENGINES.

Specification of Letters Patent. Patented Aug. 26, 1913.

1,071,602.

Application filed February 24, 1913. Serial No. 750,209.

To all whom it may concern:

Be it known that I, HAROLD BRAUNTON, a citizen of the United States, residing in the city and county of San Francisco and State of California, have invented new and useful Improvements in Ignition Systems for Rotary Oscillating-Cylinder Engines, of which the following is a specification.

This invention relates to an ignition system for rotary, oscillating cylinder engines.

10 The object of this invention is to provide an ignition mechanism particularly constructed for application to the above named type of revolving cylinder engines.

15 Another object of the invention is to so construct the spark gap portion of the mechanism that it may be mounted in the head portion of the pistons, where the spark will be least exposed to the fouling action of such materials as carbon and lubricating oils, which generally collect in the outer ends of the cylinders, being constantly forced outward by the centrifugal action.

20 The invention consists of the parts and the construction and combination of parts 25 as hereinafter more fully described and claimed, having reference to the accompanying drawings, in which—

Figure 1 is a vertical section of the engine partly broken away showing the application 30 of the ignition mechanism. Fig. 2 is a side elevation of the engine partly broken away. Fig. 3 is a section on line x—x,

Fig. 1.

35 Referring to the drawings, A indicates in general a revolving cylinder engine of the two-cycle type, in which the cylinders are pivotally mounted by trunnion members 2 in an annular casing 3, suitably journaled 40 on a stationary crank-shaft 4. The stationary crank-shaft 4 is secured by a nut 6 to a supporting frame 7.

45 The pistons in this engine are here shown as secured upon the outer ends of a series of hollow piston rods 8 which project through 50 stuffing-boxes 9, formed in the lower cylinder heads, and are connected at their lower ends to a master connecting bearing 10. The ends of the piston rods are formed with right angular bearing extensions, as indicated at 11, for this purpose. From this it can be seen that the pivotal mounting of the cylinders permits a direct connection between the pistons and crank-shaft.

55 An explosive mixture to drive the engine may be admitted to the cylinders in any

suitable manner, or, as here shown, gas may be admitted to the cylinders through the hollow trunnion members where it is ignited at the point of high compression by an ignition mechanism generally indicated at B. This mechanism forms the subject-matter of the application.

Electric current for the operation of the ignition system here shown may be generated by a magneto positively driven in connection with the engine; the primary circuit of this magneto being broken by the magneto circuit breaker as many times each revolution as there are cylinders to be fired. One secondary terminal of the magneto is grounded on the engine frame as indicated at 12, the other secondary circuit being connected to a stationary brush 13, suitably secured upon a bracket 14 forming part of the stationary supporting frame 7. The brush 13 is so positioned that it will contact with a continuous commutator ring 15 mounted in an annular insulating ring 16 secured to the outer face of the revolving casing 3. The continuous commutator ring 15 is connected with a secondary brush or wiper 17, secured to the inner face of the revolving casing 3, and is also insulated from same by a suitable insulation indicated at 18. The wiper or brush 17 being secured to the revolving casing 3 will consequently turn around the common center of the crank-shaft and will in its revolution contact with a second annular, stationary, continuous 90 commutator ring 19 suitably mounted in a stationary, circular insulating disk 20, secured on the crank 4.

The stationary commutator ring 19 is connected, as indicated at 21, with a stationary brush 22, which in turn contacts with an insulated commutator ring 23 secured on the outer face of the master connecting bearing 10. The commutator ring 23 is provided with a series of contact members 24, one for each cylinder, which in turn are so positioned as to form a contact with a series of heads 25 formed on the ends of a series of electrodes 26. The electrodes 26 are in turn mounted in a suitable insulating material, indicated at 27, forming a filler between the electrodes and the walls of the hollow piston rods 8. The insulating material, together with the electrodes 26, is secured by nuts 28 screwed into the heads 110 of the pistons. The nuts 28 may also be provided with the secondary terminals 29

forming the opposite electrodes of the spark gap; the electrodes 29 forming the ground or return circuit through the engine.

In operation, gas is admitted to the cylinders through the hollow trunnion members 2 and is ignited at the point of high compression by the electric current jumping the spark gap formed between the terminals of the electrodes 28 and 29, each cylinder being fired as it comes into firing position. This position only occurs when a cylinder with corresponding segment 24 registers with the stationary brush 22 which allows the current from the magneto to pass through the stationary brush 13, annular ring 15, revolving brush 17, stationary ring 19, stationary brush 22, and segment 25, which in turn is connected with one of the electrodes 26. The current then traverses the spark gap between the electrodes 26 and 29 which completes the circuit. Thus each cylinder will be fired as its corresponding segment 24 comes into register with the stationary brush 22 which completes the circuit through the electrodes.

The sparking mechanism generally employed in connection with revolving cylinder engines has always been subjected to the fouling action of such materials as carbon and lubricating oils, which generally collect in the outer ends of the cylinders, being constantly forced outward by the centrifugal action. Any excessive collections is thus very liable to foul the sparking mechanism generally employed, as it is necessary to maintain the spark plug or similar mechanism somewhere within the range of the compression space. The ignition mechanism constructed and applied as here shown in the head of the piston will naturally be further removed from contact with any collected material than is possible with plugs or similar mechanism generally employed, and it will, therefore, be more reliable and less apt to short circuit or foul by not being as likely to come into contact with any collected foreign material. The outer ends of the cylinders may also be provided with removable caps or plugs 30 through which access may be had to inspect or adjust the electrodes.

By referring to Fig. 2 it will be seen that the contact segments 24 and the commutator ring 23 are elongated. This elongation of the contact members 24 is provided for the purpose of permitting the spark to be advanced or retarded, this being accomplished in any suitable manner as, for instance, by advancing or retarding the circuit breaker on the magneto.

I wish it understood that various changes in form, proportions and minor details of construction may be resorted to within the scope of the appended claims and that I do

not wish to limit myself to the specific design and construction here shown.

Having thus described my invention, what I claim and desire to secure by Letters Patent is—

1. In an internal combustion engine, the combination of a cylinder, a piston in said cylinder, a hollow piston rod connecting the piston with the crank-shaft, an electrode secured in said rod projecting through the upper face of the piston and insulated from the rod and piston, a secondary electrode grounded on the piston, and means for closing an electric circuit through said electrodes. 70

2. In a rotary, oscillating cylinder combustion engine, the combination of a plurality of cylinders, pistons within said cylinders, a stationary crank-shaft, a master connecting bearing mounted on said shaft, 75 hollow piston rods connecting the pistons with the master connecting bearing, an insulating material within said rods, electrodes mounted in said insulating material, secondary electrodes grounded on the pistons, 80 and means for closing an electric circuit through said electrodes.

3. In a rotary, oscillating cylinder combustion engine, the combination of a plurality of cylinders, pistons within said cylinders, a stationary crank-shaft, a master connecting bearing mounted on said shaft, 95 hollow piston rods connecting the pistons with the master connecting bearing, an insulating material within said rods, electrodes mounted in said insulating material projecting through the ends of the rods, secondary electrodes grounded on the pistons and positioned so as to form a spark gap between the electrodes, and means 100 mounted with relation to the lower ends of piston rods for closing a circuit through the lower terminals of the insulated electrodes. 105

4. In a rotary, oscillating cylinder combustion engine, the combination of a plurality of cylinders, pistons within said cylinders, a stationary crank-shaft, a master connecting bearing mounted on said shaft, 110 hollow piston rods connecting the pistons with the master connecting bearing, an insulating material within said rods, electrodes mounted in said insulating material projecting through the ends of the rods, secondary electrodes grounded on the pistons and positioned so as to form a spark 115 gap between the electrodes, a commutator ring secured on one side of the master connecting bearing, a series of contact members in said ring one for each cylinder, means connecting the lower terminals of the insulated electrodes with the contact members, and means for closing a circuit through said contact members. 120

5. In a rotary, oscillating cylinder combustion engine, the combination of a plu- 130

rality of cylinders, pistons within said cylinders, a stationary crank-shaft, a master connecting bearing mounted on said shaft, hollow piston rods connecting the pistons 5 with the master connecting bearing, an insulating material within said rods, electrodes mounted in said insulating material projecting through the ends of the rods, secondary electrodes grounded on the pistons 10 tons and positioned so as to form a spark gap between the electrodes, a commutator ring secured on one side of the master connecting bearing, a series of contact members in said ring one for each cylinder, means

connecting the lower terminals of the insulated electrodes with the contact members, a brush mounted on the stationary crank-shaft and insulated from the shaft adapted to contact with each contact member in succession, and means for closing a circuit 15 through the brush.

In testimony whereof I have hereunto set my hand in the presence of two subscribing witnesses.

HAROLD BRAUNTON.
